OIL WELL PUMP

Francis E. Steele, Shreveport, La., assignor to
 Phillips Petroleum Company, a corporation of
 Delaware

Application March 14, 1938, Serial No. 195,902

3 Claims. (Cl. 103—240)

This invention relates to oil well pumps and more particularly to an oil well pump employing gas pressure to lift the oil from the well.

An important object of the invention is to provide a pumping apparatus which may be located at the bottom of the well and having a cylinder means which, by rotation imparted to the cylinder from the surface of the ground, may alternately be connected with gas under pressure to force oil from the accumulation chamber of the pump and to close off the gas pressure to allow the accumulation chamber to be exhausted of gas and to refill with oil.

A further object of the invention resides in its simplicity of design, the small number of working parts, economics of operation and the fact that it provides for surface control of a bottom hole gas operated displacement pump.

Other objects and advantages of the invention will be apparent during the course of the following description.

In the accompanying drawings, forming a part of this specification, and in which like numerals are employed to designate like parts throughout the same,

Fig. 1 is an elevation view of the pump structure showing the pump in the well tubing strings and surface equipment,

Fig. 2 is a vertical sectional view of the pump apparatus showing the cylinder in position to exhaust the accumulation chamber of gas,

Fig. 3 is a vertical sectional view of the pump apparatus showing the cylinder in position to allow the gas under pressure to enter into the accumulation chamber.

Fig. 4 is a transverse sectional view through the pump apparatus taken on the line 4—4, of Fig. 3,

Fig. 5 is a transverse sectional view through the pump apparatus taken on the line 6—6, of Fig. 3,

Figure 6 is a transverse sectional view of the pump set when the pump mechanism is removed, taken on the line 5—5 of Figure 3.

Referring now more particularly to the drawings, the numeral 10 represents the casing which lines the well hole and extends from the surface of the ground to the well bottom. The outer and inner tubing strings are represented by the numerals 11 and 12 having a space 13 therebetween which communicates with a source of pressure gas through the inlet pipe 15. The space 14 between the outer tubing string 11 and the casing 10 communicates with the outlet pipe 16 and serves to conduct the gas exhausted from the

accumulation chamber to the atmosphere. Pipe 17 serves to conduct the oil flowing from the reservoir through the tubing string 12, to storage.

Mounted on the surface of the ground is the motor 18 which rotates the gear 19. Gear 19 in turn rotates the gear 20 which has gear 21 keyed to the same shaft. Gear 21 meshes with gear 22 which is keyed rigidly to the inner tubing string 12. Inner tubing string 12 is supported by bearings 23 and is rotated by the motor and gear mechanism to turn the cylinder in the pump mechanism in the bottom of the well to be more fully explained later.

The casing 11 extends down into the well hole 24 and has the bull plug or protecting device 25 mounted thereon which contacts the bottom of the well and serves to protect the standing valve 26 from the mud or accumulations of sand in the bottom of the hole. Above the standing valve 26 is a space 27 which is the accumulation chamber when the pump mechanism is mounted in the well. Extending inwardly from the tubing string 11 and at the top of the accumulation chamber is a flange 28 which has a seat portion to receive the pump mechanism 30 when lowered within the outer tubing 11. The flange 28 has a channel or outlet portion 29 therethrough which passage communicates with the space 14 between the casing 10 and outer tubing 11.

The flange or projection 50 on the seat 28 aligns the barrel 32 when placed on the seat 28 and insures against rotation of the barrel if the plug should become stuck to the barrel.

Mounted on the end of the inner tubing 12 by means of screw threads 31 is the pump mechanism 30 which has a portion on the end thereof to seat and seal with the seat 28 on the flange in the outer string of tubing 11. The pump mechanism 30 is made up of an outer cylindrical member or barrel 32 which has the inner cylindrical plug member 33 rotatably mounted therein. The two members 32 and 33 are held in assembled relation by the screw thimble 34 which is attached by the screw threads 35 to the outer cylindrical member or barrel 32 and the shoulder portion of the thimble contacts the upper end of the plug to hold the same assembled in the member 32. Bearings 36 are mounted in the space 37 in the thimble 34 to relieve friction and add support to the inner tubing 12 when the tubing is rotated.

In the side wall of the member 32 is the passage 40 which communicates with the passage 13 and the passage 41 in the plug member 33. The 55

member 32 has the passage 42 in the opposite side from the passage 40, which communicates with the passage 40 through the passage 41 in the plug member when the passages are aligned 5 as shown in Fig. 4. Passage 43 extends vertically through the member 32 and terminates in the lower end of the member 32, thus establishing communication between the accumulation chamber and the space 13 when the plug is in the position shown in Fig. 3. In the lower end of the 10 member 32, is the branch passage 44 which connects with the passage 43 to establish communication through the passage 45 in the plug, passage 46 in the lower end of the member 32 and 15 thence through passage 29 in the seat portion to the space 14 to exhaust the pressure gas from the accumulation chamber when the plug is in the position shown in Fig. 2.

The plug member has a central passage 49 extending 20 the length of the plug and a nipple 47 projecting into the accumulation chamber with a check valve 48 therein, to conduct the flow of oil from the accumulation chamber 27 to the inner tubing string 12 and then to the surface of the 25 ground. The check valve 48 prevents flow of the oil from the tubing string 12 back into the accumulation chamber.

In operation, the outer tubing string 11 has 30 already been set within the well and the pump mechanism 30 on the end of the tubing string 12 has been lowered in the tubing 11 and seated on the seat 28. The pump mechanism 30 and the inner tubing 12 can thus be removed from the well without removing the outer tubing 11. 35 The gearing at the surface of the ground has been assembled and the string of tubing 12 with the plug 33 on the end thereof is ready to be rotated. The pressure in the well is such that the accumulation chamber 27 will be filled with liquid and as the plug rotates, at one point in 40 its rotation, the passage 41 in the plug will align with the passages 40 and 42, thus placing the space 13 with the gas under pressure from the line 15 in communication with the accumulation chamber 27 to force the liquid accumulated in the chamber through the nipple 47, check valve 48, passage 49, into the inner tubing 12 and thus to the surface of the ground. Fig. 4 shows the alignment of the passages when the plug is in this position of its rotation. As the plug continues 45 to rotate the passage 41 will move out of alignment with passages 40 and 42, thus closing off the supply of gas under pressure to the accumulation chamber. As the plug continues to rotate, the passage 44 in the plug is brought into 50 alignment with passages 43 and 46, thus placing the accumulation chamber in communication with the space 14 through passages 43, 44, 45, 46 and 29 to exhaust the accumulation chamber of gas either high pressure or reservoir, thus allowing 55 the chamber to be filled again with liquid from the well. The plug continues to rotate thus making the operation an alternate one of admitting gas under pressure to the accumulation chamber and exhausting the chamber to allow the chamber to fill again with liquid. The speed with which the inner tubing is rotated is dependent upon the conditions found in the well, but for general practice it has been found that a slow speed is preferable, as an example, approximately 60 two to twenty revolutions per minute.

It is noted that the plug 33 is cut away around the openings 41 and 45 so that the ports 41 and 45 are closed for only a very short period of the rotation of the plug. If desired, an expansion joint 51 may be incorporated in the rotatable

tubing string to care for any expansion or contraction of the tubing. Applicant makes no claim to any particular type of expansion joint but it must be one that will allow expansion and contraction of the tubing string and at the same time transmit torque.

It is to be understood that the form of my invention, herewith shown and described, is to be taken as a preferred example of the same, and that various changes in the shape, size and arrangement of parts may be resorted to, without departing from the spirit of my invention or the scope of the subjoined claims.

Having thus described my invention, I claim:

1. In a deep well lifting means, inner and outer tubing members, a barrel member mounted on the end of the inner tubing member, a shoulder on the inner wall of the outer tubing member providing a seat for the barrel member, said seat portion having a transverse opening there-through, a plug member attached to the inner tubing member having a longitudinal conduit through the center thereof and rotatable in said barrel by means of turning the inner tubing member from the surface of the ground, a liquid accumulation chamber located below said barrel member, a longitudinal conduit in the bottom of the barrel member connecting the accumulation chamber with the conduit in the center of the plug member and the inner tubing member, an opening in the upper end of the barrel connecting with the space between the inner and outer tubing members, a conduit in the wall of the barrel having a transverse portion directly opposite the first named opening in the barrel and a portion running longitudinally of the barrel connecting with the top of the accumulation chamber, a second passage in the lower portion of the barrel connecting with the transverse opening in the seat portion, transverse passages in the upper and lower portions of the plug member alternately aligning with the openings in the barrel upon rotation of the plug member to admit gas under pressure from the space between the inner and outer tubing to the accumulation chamber to force the liquid therein upwardly through the lower end of the barrel plug member and into the inner tubing and then by continuing rotation of the plug member closing off said gas admission openings and opening the passages in the lower portion of the barrel to exhaust the gas under pressure from the accumulation chamber to the formation.

2. In a deep well lifting means, inner and outer tubing members, a barrel member mounted on the end of the inner tubing member, a shoulder on the inner wall of the outer tubing member providing a seat for the barrel member, said seat portion having a transverse opening there-through, a plug member attached to the inner tubing member having a longitudinal conduit through the center thereof and rotatable in said barrel by means of turning the inner tubing member from the surface of the ground, a liquid accumulation chamber located below said barrel member and formed in the outer tubing by the barrel member seating on the shoulder in the outer tubing, a longitudinal conduit in the bottom of the barrel member connecting the accumulation chamber with the conduit in the center of the plug member and the inner tubing member, an opening in the upper end of the barrel connecting with the space between the inner and outer tubing members, a conduit in the wall of the barrel having a transverse portion directly opposite the first named opening in the barrel

and a portion running longitudinally of the barrel connecting with the top of the accumulation chamber, a second passage in the lower portion of the barrel connecting with the transverse 5 opening in the seat portion, transverse passages in the upper and lower portions of the plug member alternately aligning with the openings in the barrel upon rotation of the plug member to admit gas under pressure from the space between 10 the inner and outer tubing to the accumulation chamber to force the liquid therein upwardly through the lower end of the barrel plug member and into the inner tubing and then by continuing rotation of the plug member closing off 15 said gas admission openings and opening the passages in the lower portion of the barrel to exhaust the gas under pressure from the accumulation chamber to the formation.

3. In a deep well lifting means, inner and 20 outer tubing members with a flexible joint in the inner member to allow for expansion and contraction of the inner tubing, a barrel member mounted on the end of the inner tubing member, a shoulder on the inner wall of the outer tubing member providing a seat for the barrel member, said seat portion having a transverse opening therethrough, a plug member attached to the inner tubing member having a longitudinal conduit through the center thereof and rotatable 25 in said barrel by means of turning the inner tubing member from the surface of the ground, a liquid accumulation chamber located below said

barrel member and formed in the outer tubing by the barrel member seating on the shoulder in the outer tubing, a longitudinal conduit in the bottom of the barrel member connecting the accumulation chamber with the conduit in the center of the plug member and the inner tubing member, an opening in the upper end of the barrel connecting with the space between the inner and outer tubing members, a conduit in the wall of the barrel having a transverse portion directly opposite the first named opening in the barrel and a portion running longitudinally of the barrel connecting with the top of the accumulation chamber, a second passage in the lower portion of the barrel connecting with the transverse 10 opening in the seat portion, transverse passages 15 in the upper and lower portions of the plug member alternately aligning with the openings in the barrel upon rotation of the plug member to admit gas under pressure from the space between 20 the inner and outer tubing to the accumulation chamber to force the liquid therein upwardly through the lower end of the barrel plug member and into the inner tubing and then by continuing rotation of the plug member closing off 25 said gas admission openings and opening the passages in the lower portion of the barrel to exhaust the gas under pressure from the accumulation chamber to the formation.
